Register Company, Dayton, Ohio, a corporation
of Maryland

Application June 4, 1949, Serial No. 97,196

5 Claims. (Cl. 51—8)

1

This invention relates to improvements in the construction of vapor blast nozzles for producing a wide curtain spray of uniform density.

Vapor blast processes are used to make the surfaces of metal parts metallurgically clean, prior to electro-plating and for producing certain finishes. To produce an even finish over the entire surface of the metal of wide dimensions, it is necessary to produce a vapor spray of an abrasive mixture in the form of a curtain extending over the entire width of the part so that no overlapping is produced. In the nozzles known in the prior art, the width of the spray produced was so limited that only a narrow curtain could be produced, resulting in finishes that were not uniform in prepared work of dimensions wider than the width of the curtain.

It is therefore an object of the invention to provide a vapor spray nozzle for producing a wide curtain spray of abrasive mixture.

A specific object of the invention is to provide a vapor spray nozzle mixture chamber and an air chamber adjustable relatively therein to provide a curtain spray.

Another object of the invention is to provide outlet slots for an air chamber and a mixture chamber constructed and correlated in relation with each other so as to produce a wide and uniform curtain spray.

With these and incidental objects in view, the invention includes certain novel features of construction and combinations of parts, preferred forms or embodiments of which are hereinafter described with reference to the drawings which accompany and form a part of this specification.

Of said drawings:

Fig. 1 is a sectional view through the nozzle, taken on line 1—1 of Fig. 4, and looking in the direction of the arrow.

Fig. 2 is a bottom view of the nozzle.

Fig. 3 is a detailed sectional view of a modified form of nozzle throat.

Fig. 4 is a longitudinal cross-sectional view taken on line 4—4 of Fig. 1 and looking in the direction of the arrows.

General description

In use, parts made of metal which are plated and highly polished (such as, for example, chromium finishes) upon being handled soon become unsightly from finger prints or other blemishes. To avoid this, and/or to produce a satin-like finish, the metal parts are first processed by slightly abrading the surface. Thereafter, when such parts are plated, a satin-

like finish is produced. One problem in abrading such parts in the prior art was that, in performing the abrading operations, streaks, or other blemishes, would appear, which were due to the requirement that the parts had to be sent through the spray two or more times, in those cases where the parts had a dimension wider than the width of the curtain spray produced by conventional spray nozzles.

10 To overcome the objections to conventional nozzles, applicants have provided a nozzle in which an air outlet is located in respect to an abrasive mixture outlet to provide a uniform curtain of any desired width. By way of illustration, the nozzle is herein disclosed to produce a curtain approximately five and one-half inches wide when located five inches from the work to be processed. In processing the surface of the work, the work is fed through the spray curtain at a steady rate of speed, the rate being determined by the finish desired.

Detailed description

25 A mixture chamber 10 is formed by using a tubular member 11, which member may be a piece of standard pipe, threaded at each end to receive caps 12. The tubular member 11 is slotted to form an opening to receive plates 13 and 14, which are brazed, or welded, to the two sides 30 of the opening. Shoes 15 and 16 are accurately machined and attached to the plates 13 and 14, respectively, by screws 17 and 18. The shoes 15 and 16 may be made of any suitable abrasion-resistant material, such as tempered metal or rubber, the latter giving excellent wearing qualities. Retaining plates 19 and 20 are mounted on the plates 13 and 14, respectively, to retain the shoes 15 and 16 in position. End walls 22 are secured to the plates 13 and 14 to form closures 35 at each end of a slot 23 formed by shoes 15 and 16. Two hoppers 24, of at least the length of the slot 23, are provided, having narrow openings 25 leading abrasive mixture into the mixture chamber 10. Suitable slits are cut into the pipe 40 11 to receive the lower ends of the hopper in such a location that the mixture will form a curtain and fall on the surfaces 26 of the plates 13 and 14. Experiment has shown that, in a spray nozzle of the dimensions shown herein, the shoes 15 and 16 should be provided with rounded corners 27, and that the radii of the corners 27 45 should be approximately five-sixteenths of an inch for best results.

Mounted within the mixture chamber 10 is an air chamber 30, which chamber is constructed

from a tubular piece such as a pipe 31, closed at each end by plugs 32, threaded to enter inside threads in the pipe 31. Openings 33 to fit an end wrench form one method of tightening the plugs 32 in the ends of the pipe 31.

The pipe 31 is slotted to receive two shoes 34, which are machined and brazed, or otherwise securely fastened therein, so as to be air-tight. The shoes 34, after being mounted in the pipe 31, form an air jet slot 35 to guide compressed air through the slot 23, to vaporize the abrasive mixture in the chamber 10 and to force the vaporized mixture therethrough. The walls of the air jet slot 35 must be parallel at least one-eighth of an inch long and machined extremely smooth. The air jet slot 35 must also be in exact alignment with the abrasive mixture slot 23 to operate the nozzle successfully.

Mounted, so as to be in exact alignment with the air jet slot 35, are a plurality of air intake pipes 36. As illustrated herein, four pipes 36 are shown, which are sufficient for a nozzle intended to form a curtain of vapor five and one-half inches wide. The number of pipes to be used will vary with the width of the curtain to be formed.

A dispersion rod 40 is freely mounted in the caps 32 in the center of the air chamber 30 to properly disperse the air forced through the pipes 36.

To provide a solid connection to the pipe 31 for the pipes 36, a bar 37 is brazed to the pipe 31, both of which are drilled and tapped to receive the pipes 36 as shown.

The spacing of the air jet slot 35 from the abrasive mixture slot 23 is critical for best results. To enable the operator to get the best spacing between the two slots, the assembly including the pipe 31, the shoes 34, and the pipes 36 is adjustably mounted in the mixture chamber 10. To provide for such adjustment, the pipes 36 are slidably mounted in a plate 38 brazed to the tubular member 11. Set screws 39 provide a means to maintain the adjustable unit in the proper position.

A modified form of the throat construction is shown in Fig. 3, where the shoes 15 and 16 are replaced by rotatably mounted rods 56. The rods 56 are provided with reduced ends to fit bearings in the walls 22. For best results, it has been found that the rods should be made from five-eighths-inch diameter stock.

While the forms of mechanism herein shown and described are admirably adapted to fulfill the objects primarily stated, it is to be understood that it is not intended to confine the invention to the two forms or embodiments disclosed herein, for it is susceptible of embodiment in various other forms.

What is claimed is:

1. In a vapor spray nozzle, the combination of a plurality of hoppers having outlet openings constructed to release a curtain of abrasive mixture therefrom, a mixing chamber into which said curtain of mixture is released, an air jet chamber adjustably mounted within the mixing chamber, a dispersion means rotatably mounted in the center of the air jet chamber to disperse the air in the air jet chamber, a plurality of air conduits to supply compressed air to the air jet chamber, an outlet from the air jet chamber consisting of a narrow slot, and an outlet from the mixing chamber in exact alignment with the outlet from the air jet chamber, whereby the air forced through the first-named outlet atomizes the abrasive mix-

ture and forces the mixture through the second-named outlet to form a vapor curtain.

2. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber mounted within the mixing chamber, a dispersion means rotatably mounted in said air jet chamber to disperse the air in the air jet chamber, a plurality of air conduits through which compressed air is supplied to the air jet chamber, a narrow slot in the air jet chamber, and a slot 10 located in the mixing chamber in exact alignment with the slot in the air jet chamber, whereby compressed air is guided from the air jet chamber through the abrasive mixture and the slot in the mixing chamber to form a vapor curtain.
3. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber within the mixing chamber equal in width to the inside width of the mixing chamber, a dispersion means consisting of a rod rotatably mounted 25 in said air jet chamber to disperse the air in the air jet chamber, a plurality of air conduits through which compressed air is supplied to the air jet chamber, a narrow slot in the air jet chamber, and a slot located in the mixing chamber 30 in exact alignment with the slot in the air jet chamber, whereby compressed air is guided from the air jet chamber through the abrasive mixture and the slot in the mixing chamber to form a vapor curtain.
4. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber 35 within the mixing chamber equal in width to the inside width of the mixing chamber, a dispersion means rotatably mounted in said air jet chamber to disperse the air in the air jet chamber, a plurality of air conduits through which compressed air is supplied to the air jet chamber, a narrow slot in the air jet chamber, and a slot located in the mixing chamber 40 in exact alignment with the slot in the air jet chamber, whereby compressed air is guided from the air jet chamber through the abrasive mixture and the slot in the mixing chamber to form a vapor curtain.
5. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber 45 within the mixing chamber equal in width to the inside width of the mixing chamber, a dispersion means rotatably mounted in said air jet chamber to disperse the air in the air jet chamber, a plurality of air conduits through which compressed air is supplied to the air jet chamber, a narrow slot extending the full width of the air jet chamber, and a slot located in the mixing chamber 50 in exact alignment with the slot in the air jet chamber, whereby compressed air is guided from the air jet chamber through the abrasive mixture and the slot in the mixing chamber to form a vapor curtain.
6. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber 55 within the mixing chamber equal in width to the inside width of the mixing chamber, a dispersion means rotatably mounted in said air jet chamber to disperse the air in the air jet chamber, a plurality of air conduits through which compressed air is supplied to the air jet chamber, a narrow slot extending the full width of the air jet chamber, and a slot in the mixing chamber in exact alignment with the slot in the air jet chamber, whereby compressed air is guided from the air jet chamber through the abrasive mixture and the slot in the mixing chamber to form a vapor curtain.
7. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber 60 within the mixing chamber equal in width to the inside width of the mixing chamber, a dispersion means rotatably mounted in said air jet chamber to disperse the air in the air jet chamber, a plurality of air conduits through which compressed air is supplied to the air jet chamber, a narrow slot extending the full width of the air jet chamber, and a slot in the mixing chamber equal in width to the slot in the air jet chamber and in exact alignment therewith, whereby compressed air is guided from the air jet 65 chamber through the abrasive mixture and the slot in the mixing chamber to form a vapor curtain.
8. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber within the mixing chamber equal in width to the inside width of the mixing chamber, a dispersion means rotatably mounted in said air jet chamber to disperse the air in the air jet chamber, a plurality of air conduits through which compressed air is supplied to the air jet chamber, a narrow slot in the air jet chamber, and a slot 70 in the mixing chamber equal in width to the slot in the air jet chamber and in exact alignment therewith, whereby compressed air is guided from the air jet chamber through the abrasive mixture and the slot in the mixing chamber to form a vapor curtain.
9. In a vapor spray nozzle, the combination of hoppers, each having an outlet opening at the bottom thereof of widths equal to the width of the hoppers to release curtains of abrasive mixture therefrom, a mixing chamber into which said curtains of mixture are released, an air jet chamber 75 within the mixing chamber equal in width to the inside width of the mixing chamber, a dispersion means rotatably mounted in said air jet chamber to disperse the air in the air jet chamber, a plurality of air conduits through which compressed air is supplied to the air jet chamber, a narrow slot in the air jet chamber, and a slot in the mixing chamber equal in width to the slot in the air jet chamber and in exact alignment therewith, whereby compressed air is guided from the air jet chamber through the abrasive mixture and the slot in the mixing chamber to form a vapor curtain.

chamber through the abrasive mixture and the slot in the mixing chamber to form a vapor curtain, the adjacent inner corners of the walls forming the slot in the mixing chamber being rounded.
